(57) **CLAIM**

The ornamental design for a multi-beverage drink machine, as shown and described.

DESCRIPTION

FIG. 1 is a front perspective view of a multi-beverage drink machine showing a first embodiment of my new design; FIG. 2 is a perspective view thereof with the beverage support in an alternate position;

FIG. 3 is a front view of FIG. 1;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a front perspective view of a multi-beverage drink machine showing a second embodiment of my new design; FIG. 10 is a perspective view thereof with the beverage support in an alternate position;

FIG. 11 is a front view of FIG. 1;

FIG. 12 is a rear view thereof;

FIG. 13 is a top plan view thereof;

FIG. 14 is a bottom plan view thereof;

FIG. 15 is a right side view thereof; and,

FIG. 16 is a left side view thereof.

The broken lines represent environment or structure and do not form a portion of the claimed design.

The use of stippling is used to indicate a contrast in color and/or materials with the line-shaded parts of the multi-beverage drink machine.
